UNITED STATES PATENT OFFICE.

PHILIP REISS, OF NEW YORK, N. Y.

GARMENT POCKET.

Application filed March 16, 1928. Serial No. 262,077.

The present invention relates to pockets for garments and has particular reference to pockets for outer garments such as coats and the like and has for a principal object to 5 provide a double pocket structure, one of said pockets opening along its upper edge and the other of said pockets being disposed immediately rearwardly of said first named pockets with the inner layer of the pocket 10 material forming the outer layer of said last named pocket and said last named pocket having its opening arranged along its rearwardly disposed side edge.

A further object of the invention is to provide 15 a pocket structure of this character in which the outwardly disposed pocket is provided with a flap forming a closure for the pocket opening and within which pocket articles may be safely carried and with the 20 other of said pockets being adapted to receive the hands of the wearer so as to form a protection therefor, the interior of each of said pockets being entirely isolated from each other so as to prevent the possibility of the 25 accidental removal of the articles from one of the pockets by the movement of the hands in the other thereof.

An additional object is to provide a pocket 30 structure for garments of a simple and practical construction, which is neat and attractive in appearance, which may be formed in the garment without materially increasing the cost of manufacture thereof and otherwise well adapted for the purposes for 35 which the same is intended.

Other objects and advantages reside in the special construction, combination and arrangement of the various elements forming the invention as more fully hereinafter 40 described and claimed, reference being had to the accompanying drawings forming part hereof, wherein like numerals refer to like parts throughout, and in which:

In the drawings:

45 Figure 1 is a fragmentary plan view of a portion of a garment provided with a double pocket constructed in accordance with my invention,

Figure 2 is a horizontal sectional view 50 through the pocket, and

Figure 3 is a vertical sectional view there- 55 through.

Referring now to the drawing in detail, I have illustrated by invention arranged as 55 a part of a garment indicated at 5, which

in its present embodiment is represented as a coat of the wind breaker or lumber jack type, it being understood however, that the invention is equally well adapted for use in conjunction with various other types of garments.

The invention comprises a double pocket including an inner pocket 6 and outer pocket 7, the inner pocket being formed by a vertically extending opening in the outer layer 8 of the garment whereby to form a pocket opening 9, and arranging a section of material 10 inwardly with respect to the material 8 with its end edges sewed as at 11 to the inner edges of the opening 9 whereby to form the inner 60 pocket 6 of the material 10. The upper and lower edges of the pocket material 10 are also sewed to the garment material 8 as indicated at 11'. The outer pocket 7 is formed by sewing a piece of pocket material 12 along its side and bottom edges to the outer surface of the garment material 8, the upper edge of the material 12 being left unsecured whereby to provide the pocket opening 13 for the outer 65 pocket 7.

Immediately above the upper edge of the outer pocket 7 is arranged a flap 14 secured along one edge to the outer surface of the garment material 8 and adapted to extend over the opening 13 in a manner for closing the same, said flap and said outer pocket 11 being provided with cooperating sections of a snap fastener 15 whereby to permit the flap 14 to be releasably secured over said pocket opening 13.

As clearly illustrated in Figures 1 and 2 of the drawings the rear side edge of the outer pocket 7 is disposed in alinement with the edge of the opening 9 for the inner pocket 6. A strip of binding material 16 may be placed along such edge of the outer pocket 7 for the purpose of reinforcing the material and preventing wear along such edge of the outer pocket.

As shown in Figure 1 of the drawings, the area of the inner pocket 6, designated by the dotted lines 17 may be greater than the area of the outer pocket 7, although it is to be understood that the relative area of such pocket may be altered as desired.

It will be apparent from the foregoing that each of the pockets are provided with separate pocket openings, the garment material 8 serving as the dividing means for the respective pockets. The outer pocket 7 is adapted 110

particularly for the carrying of articles therein whereas the inner pocket 6, having its opening extending vertically is adapted for conveniently receiving the hands of the wearer 5 in a manner for protecting the same while the garment is being worn.

It is obvious that my invention is susceptible to various changes and modifications in construction without departing from the 10 spirit of the invention or the scope of the appended claim, and I accordingly claim all such forms of the device to which I am entitled.

Having thus described my invention, what 15 I claim as new is:

A double pocket for garments comprising a section of pocket material secured upon the inner face of the material of the garment,

said garment material having a vertically extending opening formed therein whereby to 20 provide an opening for the inner pocket material, said pocket material being folded upon itself with its edges secured at the opposite edges of the opening, a section of pocket material secured upon the outer surface of the garment material with its side and bottom edges closed and having one of its side edges disposed along the edge of the opening for 25 said inner pocket, and secured to one edge of the inner pocket material and a reinforcing strip of material arranged to provide a common reinforcement for one edge of the inner pocket opening and one edge of the outer pocket material.

In testimony whereof I affix my signature.
PHILIP REISS.
